US00D936146S

(12) **United States Design Patent** (10) Patent No.: **US D936,146 S**
(45) Date of Patent: **** Nov. 16, 2021**

(54) **GAME CONTROLLER**

(71) Applicant: **Microsoft Corporation**, Redmond, WA (US)

(72) Inventors: **Elliott Hsu**, Seattle, WA (US); **Tsitsi Kolawole**, Lynnwood, WA (US); **Joshua P. Weiher**, Seattle, WA (US); **Jonathan Shea Robinson**, Seattle, WA (US); **Aaron Schmitz**, Seattle, WA (US); **Dustin Tiffany**, Woodinville, WA (US); **Gabriel Michael Rask Gassoway**, Issaquah, WA (US)

(73) Assignee: **Microsoft Corporation**, Redmond, WA (US)

(**) Term: **15 Years**

(21) Appl. No.: **29/686,517**

(22) Filed: **Apr. 4, 2019**

(51) LOC (13) Cl. **21-01**

(52) U.S. Cl.

(57)

CLAIM

The ornamental design for a game controller, as shown and described.

DESCRIPTION

FIG. 1 is a bottom front perspective view of a game controller showing our new design;

FIG. 2 is a top front perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

(Continued)

The broken lines in the drawings depict portions of the game controller that form no part of the claimed design.

1 Claim, 8 Drawing Sheets
